UNITED STATES PATENT OFFICE

149,476

DESIGN FOR AN END COVER FOR A SUCTION CLEANER CASING OR SIMILAR ARTICLE

Henry Dreyfuss, New York, N. Y., assignor to The Hoover Company, North Canton, Ohio, a corporation of Ohio

Application August 9, 1946, Serial No. 132,404

Term of patent 14 years

(Cl. D9—2)

To all whom it may concern:

Be it known that I, Henry Dreyfuss, a citizen of the United States, residing at New York city, in the county of New York and State of New York, have invented a new, original, and ornamental Design for an End Cover for a Suction Cleaner Casing or Similar Article, of which the following is a specification, reference being had to the accompanying drawing, forming a part thereof.

In the drawing:

Figure 1 is a side elevational view of the end cover, showing my new design;

Figure 2 is an end view of the cover;

Figure 3 is a bottom view of the cover; and

Figure 4 is a perspective view of the end cover,

the broken lines showing a casing are for illustrative purposes only.

I claim:

The ornamental design for an end cover for a suction cleaner casing or similar article, substantially as shown and described.

HENRY DREYFUSS.
